COMBINED TOAST RACK AND BUTTER DISH HOLDER

John F. Bonistall, Zanesville, Ohio, assignor to Shawnee Pottery Company, Zanesville, Ohio, a corporation of Ohio

Application March 1, 1955, Serial No. 34,812

Term of patent 14 years

(Cl. D44—10)

FIG. 2

Fig. 1 is a perspective view of a combined toast rack and butter dish holder illustrating my novel design; and
Fig. 2 is an end elevational view thereof with one of the butter dishes removed.

What I claim is:

The ornamental design for a combined toast rack and butter dish holder, as shown.
